UNITED STATES PATENT OFFICE.

WILLIAM I. MANN, OF BENWOOD, WEST VIRGINIA.

TYUERE.

SPECIFICATION forming part of Letters Patent No. 313,038, dated March 3, 1885.

Application filed May 5, 1884. (No model.)

To all whom it may concern:

Be it known that I, WILLIAM I. MANN, of Benwood, in the county of Marshall and State of West Virginia, have invented a new and 5 useful Improvement in Tuyeres; and I do hereby declare that the following is a full, clear, and exact description of the same.

My invention is an improvement in tuyeres. It is adapted to be used in connection with apparatus for applying the "Bessemer process" in the manufacture of steel, in which air is driven through the charge of melted iron under treatment. As the tuyeres are necessarily below the surface of the metal during the blowing process, cessation of the blast when the charge is blown will, if the tuyeres remain in this position, cause the melted iron to run into and destroy them.

In order to avoid the necessity of a tilting converter, many expedients have been devised, 20 in connection with a fixed converter, to perfect the tuyere. One of these devices is to provide a small stream of blast passing through the tuyere after the main supply has been cut off 25 by the tuyere-plug, the stream being just large enough to keep the molten metal out of the tuyere without seriously oxidizing the iron. Such a device is shown in Letters Patent of the United States No. 271,683, and in others. 30 My object has been to simplify and improve the operating devices.

In the accompanying drawings, Figure 1 shows a section through a wind-box and part 35 of a converter to which it is attached, the apparatus for operating the tuyere being shown in side elevation. Fig. 2 is a front view of the wedge. Fig. 3 is a plan of the whole.

The plug A may be of the ordinary construction; but I prefer the construction shown in 40 the figure, which consists of a removable nose, h, held to the stem a by a sleeve, H, adapted to receive and hold it thereto. The stem and plug are bored to connect with the pipe x, attached to the stem by a suitable coupling, for 45 introducing a stream of non-oxidizing gas, or whatever may be required. A small transverse hole, b, may be provided in the nose or plug opening into the wind-box B, through which a small stream of air may be introduced 50 through the tuyere when the plug is closed and it is not desired to use the pipe x. The

wind-box is provided with an ordinary blast-pipe, C, and stuffing-box D, through which the stem a passes. To the face of the wind-box I have fixed a bridge, E, the apex of which is bored in the line of the stem a, and through it the stem passes, being adapted to move freely therein. On the bridge above and below the stem are pivoted rollers 11, adapted to bear against the face of a wedge, F. The 55 other face of this wedge bears against similar rollers, 33, pivoted on the stem in front of the collar 4, fixed thereto. Between the collar and the apex of the bridge is a spring, 5, which tends to keep the plug pressed to its seat on 60 the tuyere. The wedge F is slotted to receive the stem a, and is provided with a weight, H', sufficiently heavy to draw down the wedge, compress the spring, and draw back the plug. The wedge is connected with any suitable rope 65 and pulley or devices for raising it for the purpose of allowing the spring to close the plug upon its seat.

In the end of the coupling G, in line with the bore of the stem a, is a sight-opening, g, 70 covered by a glass plate, y.

The stuffing-box D is formed with the convex flange d for connecting it with the concave face of the wind-box. The flange is formed with holes of larger diameter than the bolts, so 75 that the stem may be adjusted in line accurately with the tuyere-opening. The enlarged holes and spherical faces permit sufficient movement for this purpose.

It will be manifest that I may apply air, 80 liquid or gaseous fuel, steam, or any liquid or gaseous substance through the pipe x, as may be desired for different purposes.

I have represented the wedge as arranged 85 in a vertical position; but it may be also placed in a horizontal position or at any angle.

I prefer the removable nose for the plug, as it may be renewed when worn without much expense, and without throwing away the whole piece.

What I claim as new, and desire to secure 90 by Letters Patent, is—

1. In combination with the tuyere of a converter or other furnace, the plug provided with the stem, a spring and wedge, and a 95 suitable bridge, substantially as described, and for the purpose set forth.

2. The combination, with the tuyere, of the plug and its stem, connected to the pipe *x*, and suitable mechanism for operating the plug, as set forth.
5. 3. In combination with the tuyere, the perforated plug and stem, the coupling having the sight-opening *g* and transparent diaphragm *y*, with mechanism, substantially as described, for operating the plug.
10. 4. The combination, with the wind-box, of the plug and its stem, and means for operating the same, and an adjustable stuffing-box, substantially as described.
5. The combination, with the tuyere and the wind-box, of the perforated plug and stem, the bridge *E*, provided with anti-friction rollers, a collar and rollers upon the stem, the spring *5*, and the wedge *F*, all substantially as described.

In testimony whereof I have signed my name to this specification in the presence of two subscribing witnesses.

WM. I. MANN.
